COMBINATION GAS AND OIL BURNER

William A. Clements, Glendale, Calif.

Application November 14, 1942, Serial No. 465,571

8 Claims. (Cl. 158—11)

This invention relates to improvements in combination gas-oil burners. It is the general object of my invention to provide a simple and inexpensive device in which conversion from one type of fuel to another may be effected without disturbing or interrupting the operation of the burner. A further object is to provide simple and convenient means for quickly effecting such conversion while the burner is in full operation. A still further object is the provision of means for feeding high or low pressure air, or both, to the burner as may be required in order to obtain a desired fuel mixture or a particular degree of gasification of liquid fuel. Another object is to provide means for adjusting the flame length to suit particular installations.

These objects, as well as the various advantageous features of the invention will be appreciated upon perusal of the following detailed description, and reference is invited to the accompanying drawing in which structures embodying the invention are illustrated.

In the drawing:

Fig. 1 is a side elevational view, partly in section, of a device embodying the invention;

Fig. 2 is a cross sectional view thereof taken substantially on line 2—2 of Fig. 1 in the direction of the arrow;

Fig. 3 shows the main portion of Fig. 1 but in a different position of adjustment and with parts broken away for the sake of clearness;

Fig. 4 is a cross sectional view taken on line 4—4 of Fig. 3; and

Fig. 5 is a fragmentary view illustrating certain minor modifications of the device.

The structure of my invention, in the form illustrated in the drawing, comprises a cylindrical casing 1, within which a sleeve valve 2 is fitted to rotate, and the latter has transversely extending therethrough a port 3 for registration with an air supply inlet 4. A tubular stem 5 extends through the center of this valve and it terminates at the front end in a nozzle 6. To facilitate rotation thereof, the valve is shown fitted with a handle 19.

Gas passes through a pipe 7 to the annular space within the stem 5, thence to flow through the nozzle 6 into a chamber 8 where it becomes mixed with the air flowing through the sleeve valve and where the firing occurs. The chamber 8 is, for this reason, termed the firing chamber of the device. A hood 9 is shown fitted to the end of the casing for use when a short flame of greater intensity is needed. But it may be removed

when not needed and is in Figs. 3 and 5 so shown removed. In a gas burner as here shown only low pressure air is required, and it is understood that conventional means should be included for properly regulating the pressure relations to suit particular furnaces and heat requirements, in addition to which the sleeve valve may be rotated to vary the flow through the port 3.

A pipe 10 extends from a fuel oil inlet into the stem 5, and it is shown fitted at the forward end with a nozzle, or spreader 11. A valve 12 controls the flow of fuel oil through this pipe and spreader. When it is found necessary to change from gas to liquid fuel, it is merely required to set a valve 13 to shut off the gas supply and to open the valve 12 to cause the liquid fuel to pass into the burner. It is, however, necessary to atomize, or rather to gasify the liquid fuel before it passes into the firing chamber, and this is accomplished by passing air under high pressure through the pipe 7 into the annular space 5^a surrounding the liquid fuel pipe 10 and thence through orifices 11^a of the spreader 11 into a chamber 14, there to strike the incoming fuel with great force. The mixture now entering the firing chamber has become sufficiently gasified or aeriform substantially to compare with the gas entering the firing chamber in the setting of the burner above first described. And as the passage of low pressure air from the inlet 4 through the sleeve valve to the firing chamber remains unchanged, it is seen that, whether gas or liquid fuel is fed to the burner, the resulting combustion remains substantially unchanged and the operation may continue without interruption. It is also important to note that this conversion is effected by the mere adjustment or the setting of two valves.

A further advantage of this arrangement is that the large volume of air entering the firing chamber remains at low pressure, and that the amount of high pressure air needed for fuel gasification is relatively very small. A considerable saving of power for air compression may thereby be effected, even when liquid fuel is used over an extended period of time.

In installations, however, where ample supply of air under high pressure is available and the feature of power conservation is not of major importance, or where facilities for concurrently supplying both high and low pressure air are not at hand, the device may readily be readjusted to fuel oil consumption in the following manner.

It is noticed that a passage 15 leads from the space within the stem 5 through the outer wall of

the sleeve valve, and that this passage in Figs. 1 and 2 is shown cut off by the outer wall of the casing 1. But the sleeve valve may be rotated until this passage opens into the air inlet 4, see Fig. 4, to permit air to pass through the latter and into the annular space surrounding the fuel oil pipe 10. The valve 13 is, at the same time, set entirely to cut off the inlet to pipe 7. The result is that air under high pressure passes through port 3, the passage 15 and the perforations 11* of the spreader into the chamber 14, there to gasify the liquid fuel sprayed thereinto. Also that the greater portion of the same high pressure air passes through the port 3 and the sleeve valve to the firing chamber 8. It is important to note, however, that the sleeve valve may be rotated to restrict the flow of air through this port, as above mentioned, without disturbing the flow through the passage 15 and that, by cutting down the flow through port 3 in this manner, the high-low air supply relation above referred to may be substantially duplicated.

It is desirable to provide a series of vanes 16 in the passage from the sleeve valve to the firing chamber, substantially as indicated in Fig. 1, for the purpose of setting up whirling movement in the air rushing through this passage and thereby more thoroughly to mix this air with the gasified fuel.

The device as hereinbefore described constitutes a short flame burner, but it may readily be converted into a long flame liquid fuel burner substantially in the manner illustrated in Fig. 5. In this drawing, the nozzle 6 has been removed and a sleeve 18 fitted to slide within the stem 5. When this change is made, the liquid fuel and air are premixed in the manner described, but because the sleeve 18 has been added, the finally mixed fuel is delivered through the end of the casing into the furnace served by the burner. In order more effectively to control the length of the flame, it is also desirable to be able to adjust the spreader 11 and the extension sleeve 18 axially within the stem 5. The fuel pipe 10 is to this end seated for axial movement in the head 17 of the inlet pipe 7 and such adjustment may readily be effected by gripping the elbow 20 of the pipe 10 which, for the purpose of this description may be considered an operating handle. It is, of course, in such case necessary to provide leakproof stuffing boxes within the head 17, but as such are commonly used, it is not thought necessary herein to make further mention thereof.

It should be clear to anyone versed in the particular art that I have provided a combination burner for gaseous and liquid fuel of simplicity and convenience of operation. Also that, whether one kind of fuel or the other is fed to the burner, substantially the same aeroform mixture can be supplied to the firing chamber by the mere setting of one or two valves.

It is not, however, my intention to be limited to the precise combinations illustrated in the drawing, but I reserve the right to embody such further modifications as will come within the scope of the claims hereto annexed.

I claim:

1. A fuel burner comprising, a casing open at the front end and having an air inlet, a sleeve valve seated for axial rotation within said casing for passing air from said inlet to said front opening, a conduit within said valve and forming part thereof terminating in a nozzle near the front

opening of the casing, a fuel conduit within said first named conduit terminating in a spreader, said valve having a passage into said first named conduit, and means for rotating said valve to bring said passage into registration with said air inlet to control flow of air through the passage and the first conduit and then through the said spreader.

2. A fuel burner comprising, a casing open at the front end and having an air inlet, a sleeve valve seated for axial rotation within said casing for passing air from said inlet to said front opening, a conduit within said valve terminating in a nozzle near the front opening of the casing, a fuel conduit within said first named conduit terminating in a spreader behind said nozzle, said valve having a passage into said first named conduit, means for rotating said valve to bring said passage into registration with said air inlet to control flow of air through the passage and the first conduit and then through said spreader, said fuel conduit being axially adjustable within the first named conduit.

3. A fuel burner comprising, a casing open at its front end and having an air inlet in its side wall, a valve fitted to rotate within said casing to control said inlet, said valve having a passage axially therethrough and a port for registration with said casing inlet for passing air through the valve to the open end of the casing, the valve having a transverse duct leading from said axial valve passage to the outer surface of the valve for registration with the casing inlet, a conduit opening into said passage, a valve in said conduit for controlling gas and compressed air supply to the passage, a liquid fuel conduit passing through said first named conduit into said valve passage, and a valve controlling flow through said liquid fuel conduit, said port and said transverse duct being so positioned that either or both may be brought into and out of registration with the casing inlet upon manual rotation of the valve.

4. A fuel burner comprising, a cylindrical casing terminating at the front end in an open end firing chamber and having an air inlet in its side wall, a sleeve valve fitted to rotate within said casing to control said inlet, said valve having a tubular stem axially extending from the rear end thereof to said firing chamber, there being between the outer surface of said stem and the inner surface of said sleeve valve an annular space opening into said firing chamber, the valve having a port through its outer wall from said annular space for registration with the casing air inlet, an oil conduit leading into said tubular stem, there being an annular space between said conduit and the inner wall of the stem, a supply pipe communicating with the annular space surrounding said oil conduit, and a valve in said pipe having gas and compressed air inlets, said valve being adjustable to open a passage from one inlet thereof or the other or from both inlets to the space surrounding the oil conduit.

5. A fuel burner comprising, a cylindrical casing terminating at the front in a firing chamber and having an air inlet through its side wall, a sleeve valve fitted to rotate within said casing to control said inlet, said valve having a tubular stem axially extending from the rear end thereof to said firing chamber, there being between the outer wall of the stem and the inner surface of the sleeve valve an annular air space opening into said firing chamber, the valve having a port through its outer wall from said annular space for registration with the casing inlet, a conduit

for passing gaseous fuel and compressed air into said tubular stem, means controlling the flow through the conduit, a valve controlled oil supply pipe extending into and axially adjustable within said tubular stem and terminating therewithin in a spreader, and a hood detachably mounted on the casing at the outer end of the firing chamber.

6. A fuel burner comprising, a cylindrical casing terminating at the front end in an open front firing chamber and having an air inlet through its side wall, a sleeve valve seated to rotate within said casing to control said inlet, said valve having a tubular stem axially extending from the rear end thereof to said firing chamber to provide an annular space encompassing said stem and opening into the firing chamber, the valve having a port through its outer wall from said annular space for registration with the casing inlet and a passage leading directly from the space within said stem to the outer surface of the valve for registration with the casing inlet, a liquid fuel conduit freely extending into the stem, and means controlling flow of fuel through said conduit.

7. A fuel burner comprising, a cylindrical casing terminating at one end in a firing chamber and having an air inlet through its side wall, a sleeve valve seated to rotate within said casing to control said inlet, said valve having a tubular stem axially extending from the rear end thereof to said firing chamber to provide around the stem 30

an annular chamber opening into said firing chamber, the valve being provided in its outer wall with a port from said chamber for registration with the casing inlet, a liquid fuel conduit freely extending into said stem, means controlling fuel flow through said conduit, a second conduit leading into the stem, and means in said second conduit adjustable to pass gaseous fuel and compressed air through the space within the stem encompassing said liquid fuel conduit to the firing chamber.

8. A fuel burner comprising, a cylindrical casing terminating in an open end firing chamber and having an air inlet through its side wall, a sleeve valve fitted to rotate within said casing to control said inlet, said valve having a tubular stem axially extending from the rear end thereof to said firing chamber, there being between the outer surface of said stem and the inner surface of the sleeve valve an annular air space opening into said firing chamber, the valve having a port through its outer wall from said annular space for registration with the casing inlet, a nozzle seatable on the end of said stem, a conduit communicating with said tubular stem, a valve controlling flow of liquid fuel through said conduit, and valve controlled means for passing gas and compressed air through said stem to the nozzle thereof.
